UNITED STATES PATENT OFFICE.

WILLIAM M. RODGER, OF WOLLASTON, MASSACHUSETTS, ASSIGNOR TO MARGARET K. FORSHEE, OF DORCHESTER, MASSACHUSETTS.

DESIGN FOR A SLIPPER.

Application filed April 21, 1924. Serial No. 9,348. Term of patent 7 years.

To all whom it may concern:

Be it known that I, WILLIAM M. RODGER, a citizen of the United States of America, residing at Wollaston, in the county of Norfolk, and State of Massachusetts, have invented a new, original, and ornamental Design for a Slipper, of which the following is a specification, reference being had to the accompanying drawing, forming part thereof.

Referring to the drawing,

The figure illustrates a perspective view of a slipper embodying my novel design.

What I claim is:

The ornamental design for a slipper, as shown.

In witness whereof I hereunto subscribe my name this 16th day of April, A. D. 1924.

WILLIAM M. RODGER.
